UNITED STATES PATENT OFFICE.

CHARLES M. BABCOCK, OF GALESBURG, ILLINOIS, ASSIGNOR OF ONE-HALF
TO JOHN C. STEWART, OF SAME PLACE.

CHECK-ROW CORN-PLANTER.

SPECIFICATION forming part of Letters Patent No. 294,839, dated March 11, 1884.

Application filed May 9, 1883. (No model.)

To all whom it may concern.

Be it known that I, CHARLES M. BABCOCK, a citizen of the United States, residing at Galesburg, in the county of Knox and State of Illinois, have invented certain new and useful Improvements in Check-Row Corn-Planters; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in check-row corn-planters; and it consists in the means used for giving the stroke or reciprocating motion to the dropping-slide, as will be hereinafter described and claimed.

20 In the drawings, Figure 1 is a plan view of a portion of a corn-planter having my improvements applied thereto. Fig. 2 is a side view of the same, a part of the bar a^2 being broken away to show the groove therein and the lower 25 arm of the bifurcated vibrating bar; and Fig. 3 is a detail view of the latch-bar, hereinafter described. Fig. 4 shows a modification, and Fig. 5 is a sectional view on line x - x , Fig. 2.

I have shown my operating mechanism 30 mounted on two side bars, a a' , connected by an intermediate cross-bar, a^2 , the said bars a a' a^2 representing a portion of the framing of a corn-planter. In the upper side of the bar a^2 , extending from the bar a , I from a 35 groove, in which the reciprocating bar b is placed and slides. The forward portion of the bar b , or that next to the bar a , is bifurcated to form the upper arm, d' , and the lower arm, b^2 . The arm b^2 is arranged wholly within 40 the groove formed in the bar a^2 , so that its upper face is flush with the upper face of the said bar, and the said arm is usually made shorter than the arm b' , as it only need extend far enough to provide a support for the cam c' , 45 which will be described. Through the arm b' , near its end, I form the elongated opening b^3 , through which is passed the bolt b^4 , which, in connection with the staple b^5 , holds the reciprocating bar within the groove in the bar a^2 .

For convenience of reference, I call the movement of the bar b toward the bar a , its "forward" and reverse movement the "backward" motion of same.

On the under side of the arm b' and near the main portion of the reciprocating bar b , I fix the cam c , the cam-surface of which is on its forward side, and is inclined forward from the point where it first receives the action of the rollers, hereinafter described, to the point where such action ceases.

On the upper side of the arm b^2 and in advance of the cam c , I fix the cam c' , the cam-face of which is on its rear side, and is inclined in a manner opposite to the cam c , as shown in Fig. 1, and for the purpose hereinafter described.

On the bolt b^4 and between the arms b' b^2 , I journal the wheel d , which rests on the plate d' , and is thereby held sufficiently high to permit its arms, hereinafter described, to move clear of the cam c' .

The wheel d is composed of the arms d^2 d^3 , crossing each other at right angles, as shown. In the outer ends of these arms d^2 d^3 , I cut slots d^4 , which admit the plate fixed on the latch-bar, hereinafter described, and the portion of the arms below the slot d^4 is formed with a shoulder or hook, d^5 , which engages or enters the recess formed in the latch-bar, as will hereinafter appear.

On the upper side of the arms d^2 , near their outer ends, I secure the pins e , preferably provided with anti-friction rollers, which engage the cam c , and on the under side of and near the outer ends of the arms d^3 are secured the pins e' , also preferably provided with anti-friction rollers, which engage the cams c' in the operation of the machine.

The knotted rope f , having buttons or knots f' , is passed around pulleys g g' , mounted on the bar a , as shown.

The latch-bar h is pivoted at one end on the pin h' , fixed on the bar a , and extends alongside the pulley g , and its side next the said pulley is rounded at the point h^2 , forming a bearing, against which the knob or knot on the rope strikes and forces the said latch-bar away, and disengages the arms of the wheel

therefrom. In the inner side of the bar h , near its free or swinging end, I cut the recess or notch h^2 , into which the hook d^3 on the arms $d^2 d^3$ extends and catches, and on the upper side of the bar I fix the plate h^4 , which enters the slots d^4 in the ends of arms $d^2 d^3$ as the wheel is revolved. The normal position of the latch-bar is that shown in dotted lines, Fig. 1, in which it is held, when not forced back in the operation of the machine, by the spring i , fixed to the bar a and bearing against the latch-bar, as shown.

The wheel d and the framing $a a' a^2$ are arranged in a horizontal position, and the reciprocating bar b is connected with the dropping-slide j through the pitman j' and pivoted or rocking lever j^2 . The lever j^2 is pivoted in suitable manner on the framing, and it is connected pivotally or in other suitable manner to the dropping-slide. The pitman j' is pivoted to the bar b , and is provided on its end with a sleeve, j^3 , which slips over the lever j^2 , and may be made fast thereto at any point above its pivotal center j^3 by means of the set-screw j^4 , so as to regulate the length of the stroke, as will be understood on reference to the drawings.

In the operation of my invention, when the locking-latch and wheel d are in the position shown in dotted lines, Fig. 1, and the hook d^3 on the arms of the wheel is engaged in the notch or recess h^2 , the friction of the rope will not revolve the wheel, which will remain stationary until the knot or button j^5 engages against the rounded bearing h^2 and forces the latch-bar back, as shown in full lines, Fig. 1, when the arm will be relieved from its connection with the latch-bar, and the button j^5 carries the arm a quarter of a revolution of the wheel, until the next following arm is engaged by the latch-bar, when the operation is repeated, the wheel d being revolved intermittently in the same direction as the machine is moved along the rope. As the wheel is revolved, the cams $c c'$ are alternately engaged by the pins on the arms $d^2 d^3$, and the bar b is moved back and forth in its reciprocating motion, which is communicated to the dropping-slide in the manner before described.

In practice, I prefer to secure the pins $e e'$ on the wheel d and the cams on the bar b , as shown in Figs. 1 and 2; but it will be understood that practically the same results would be accomplished were the cams fixed on the wheel d , as shown in Fig. 4, in which case the pins, preferably provided with the rollers, would be secured on the bar b , as indicated in dotted lines, Fig. 4. I also prefer to bifurcate the bar b , as shown; but it will be understood that the arm b' might be dispensed with, and the cam or pins might be fixed on the main

portion of the bar, as will be understood on reference to the drawings.

Having thus described my invention, what I claim, and desire to secure by Letters Patent, is—

1. In a corn-planter, the combination, with the operating-wheel having slots d^4 cut in the ends of its bars d^2 , and means whereby said wheel is connected with the dropping mechanism, and the knotted rope f , of the latch-bar h , pivoted at its rear end, a suitable supporting-spring, and the plate h^4 , mounted on the latch and arranged to enter the notches d^4 in the arms d^2 , said latch-bar being provided, near its forward end, with the notch h^2 , arranged to receive and hold the wheel-arms, and constructed in rear of said notch with the cam or inclined face h^2 , arranged in position to be engaged by the rope knots or buttons, whereby the latch is pushed back and the wheel released, all substantially as and for the purposes specified.

2. The combination, substantially as described, of the operating-wheel provided with pins or rollers secured on respectively the upper and lower sides of its alternate arms, and the reciprocating bar provided with cams secured on said bar, and arranged vertically on opposite and diametrically on the same side of the wheel, said cams being inclined in opposite directions in the plane of the wheel, and formed with bearing-surfaces on respectively their forward and rear edges, said bearing-surfaces being alternately engaged by the pins or rollers on the wheel-arms, substantially as specified, and for the purposes set forth.

3. The combination, in a corn-planter, of the wheel having its arms provided with pins or rollers $e e'$, and slotted in their outer ends, the pivoted latch-bar h , supported by spring i , and constructed with notch h^2 and inclined face h^2 , the plate h^4 , mounted on said latch and arranged to enter the notches in the wheel-arms, the bifurcated bar b , provided on its arms $b' b^2$ with cams $c c'$, inclined in opposite directions, and provided on respectively their forward and rear edges with bearing-surfaces arranged to be engaged by the pins or rollers $e e'$, the dropping-slide j , arranged parallel with the bar b , pivoted rod j^2 , secured at its rear end to the dropping-slide, and connected at its opposite end with the bar b by means of pitman j' , and adjustable sleeve j^3 , and the rope f , all arranged and operating substantially as specified, and for the purposes stated.

In testimony whereof I affix my signature in presence of two witnesses.

CHARLES M. BABCOCK.
